APPARATUS FOR FORMING, FOLDING, AND
BANDING PAPER STRIPS

Alvin A. Massini, Wheeling, W. Va.

Application September 17, 1934, Serial No. 744,311

36 Claims. (Cl. 93—1)

This invention relates broadly to paper forming and folding apparatus, and apparatus for automatically placing a retaining band about the fold for maintaining the paper in its folded relation.

In certain indoor recreational games a plurality of printed rectangularly shaped strips of comparatively heavy gauge paper are individually and removably mounted by one end upon a backing board, said strips having the opposite, or free, end thereof folded about itself and secured in folded relation by a transverse gummed retaining band. Printed on the inner surface of the folded portion of the strip and invisible to the eye by reason of the fold is information of interest pertaining to the game. Upon participating in the game, a player pulls one of the strips from the board, ruptures the paper banding seal, and unfolds the end of the strip to reveal the previously hidden printed information which informs the player of matter having to do with the further progress of the game.

It is the primary purpose of the present invention to provide an automatic machine whereby such printed strips of paper are properly formed and folded to render the printed indicia invisible to the eye and, additionally, to provide in said machine means for sealing the individual strips in folded condition preparatory to mounting the same upon an appropriate backing board.

The full nature of the invention and other features thereof will be understood from the accompanying drawings and the following description. In said drawings—

Figure 1 is a front elevation of the machine;

Figure 2 is a top plan view of the same;

Figure 3 is a rear elevation of the same;

Figure 4 is an end view of the machine with parts thereof omitted to clearly disclose the folding mechanism;

Figure 5 is a perspective view of a paper blank prior to folding and banding;

Figure 6 is the paper blank in its final folded and banded condition;

Figure 7 is a schematic view illustrating in detail the folding mechanism;

Figure 8 is an enlarged end elevation, partly in section, of a portion of the folding mechanism;

Figure 9 is a section taken on line 9—9, Fig. 8;

Figure 10 is a detail view in top plan of the fingers and reciprocating feeding slide which removes the folded ticket from the folding mechanism and presents the same to the banding mechanism;

Figure 11 is a side elevation of the revolving

banding head, parts thereof being purposely omitted to disclose the principal elements;

Figure 12 is a detail front view of a banding head, the banding rollers being shown in non-operative position;

Figure 13 is a section taken on line 13—13, Fig. 11;

Figure 14 is a partial rear view of a banding head depicting the rack and gear mechanism for operating the banding arms;

Figure 15 is an enlarged vertical sectional view of a portion of the female die plate illustrating the blank stripping angle;

Figure 16 is a detail view in side elevation of the banding paper feeding, shearing and carrying mechanism for the severed band.

Figure 17 is an end view of the same; and

Fig. 18 is an enlarged detail view of the mechanism for momentarily interrupting the forward travel of the reciprocating channel.

Referring to said drawings, the reference numeral 1 designates the bed plate of the machine which latter is provided with legs 2 and carries a framework 3 designed to support the mechanism. Extending longitudinally is a front drive shaft 4, suitably journaled in appropriate bearings provided in the frame 3, said shaft being adapted to be driven by any suitable means, as the pulley wheel 111. Carried by said shaft 4 is a spur gear 5 meshing with a second spur gear 6 carried by a rear longitudinal drive shaft 7 rotatably mounted in appropriate bearings provided in the frame, the latter shaft being adapted to rotate with the front shaft 4. As shown in Fig. 1, the back shaft 7 has a length approximating the length of the bed plate 1, while the front shaft 4 has a length somewhat less, the latter terminating at a point revealed by the collar 8.

Mounted upon the frame 3 is a flat table 26, on which table is supported a forwardly inclined hopper 9 in which the previously printed blanks 10 are received in face to back relation. Pivotally connected finger weights 11 are provided at the lower end of the hopper to maintain the blanks in uniform aligned relation. A plurality of small studs 12 are provided about the mouth of the hopper so as to prevent accidental discharge of the blanks from the hopper. A feed block 13 carried by a lever 14 pivotally attached to the frame, as shown at 15, is adapted to be presented and withdrawn from the mouth of the hopper by movement of the lever 14 about its pivot 15. A longitudinal shaft 16, suitably journaled within bearings 17, is designed to be rotated by means of the bevel gears 18, connect-

ing shaft 18 and bevel gears 20. A cam 21 carried by the shaft 16 engages a roller on the end of the lever 14 imparting operative movement to the feed block 13. The feed block 13 is connected to a vacuum line 22 having connection with an operating valve 23 connected by a supply line 24 to a vacuum tank 25, the detailed operation of the operating valve 23 being hereinafter described. Depression of the free end of the lever 14 by means of the cam 21 swings the feed block in the arc of a circle so that the same will be presented in contacting relation with the exposed blank in the mouth of the hopper. At this point vacuum is applied to the feed block so that the blank adheres to the face of the block and is removed from the hopper against the retaining force of the finger weights 11 and studs 12. Immediately following removal of the blank, the cam 21 is brought out of depressing relation with the lever 14 so that the feed block falls by gravity to the position shown in the drawings in which position the blank is deposited in a horizontal plane on the upper face of the table 26, and the vacuum force is cut off by operation of the valve 23.

Slidably mounted in spaced parallel guides 27, fixed to the upper surface of the table 26 is a rectangularly shaped pusher plate 28 designed to be reciprocated back and forth across the top 30 of the table by means of the link 29, lever 30 and cam 31, said cam being carried by the shaft 16, and being maintained in permanent contacting relation with the lever 30 by means of the retractile coil spring 31. Following depositing of the 35 blank on the table 26, as above described, the pusher plate is brought into timed operation so as to advance the deposited blank forward to a position in vertical alignment with the forming die, accurate positioning being accomplished by 40 means of the limit stops 35.

Extending upwardly from the table 26 is a pair of spaced guide pins 32 on which is vertically slidable a crosshead 33 carrying a removable male die plunger 34. The female portion of the die 45 consists of two plates 36 defining an opening to receive the die plunger 34 and registering with an opening provided in the table 26. Journalized in bearings 38 on the underside of the table 26 is a short longitudinal rocker shaft 39. Carried in 50 fixed relation by said shaft 39 on the inner end thereof is a rocker arm 40, the free, or rear, end of which carries a roller contacting a cam 41 mounted on the shaft 16, the opposite, or front, end of the rocker arm being connected to the 55 crosshead by means of a link 42. The opposite side of the crosshead 33 is connected to the rocker shaft 39 by a vertical link 43 and a horizontal link 44. Thus, rotation of the cam 41 functions to depress the male die, the depressing force being uniformly borne by each side of the crosshead 60 by means of the above described mechanism.

Depression of the male die is accomplished against the force of a pair of compression springs 45 encircling the guide pins 32 and interposed 65 between the crosshead 33 and table 26, the upward force of said springs being transmitted to the rocker arm 40 so as to maintain the latter at all times in cam-contacting relation.

In the downstroke of the male die 34, the previously positioned blank 10 is engaged and is forced downward through the opening in the female die 36 so that the blank in the confines of the female die 36 is made to conform with the shape of the male die 34. In other words, the 70 blank is given a substantially U-shape, one ver-

tical portion exceeding the length of that of the other, the shorter vertical portion having a length not to exceed the length of the bottom, or horizontal, portion, and the last two mentioned portions bearing the printed matter which is to be rendered invisible by folding the blank in a manner to obscure the same.

Located on the front of the machine below the level of the table 26 is a bearing plate 46 in which is journalized a short transverse shaft 47 carrying 10 a feed wheel 48 occupying underlying registering relation with the forming mechanism and having for one of its purposes to serve as a bottom for the forming die. The feed wheel 48 has formed in its periphery a plurality of spaced flat surfaces 15 49 and it is these flat surfaces of the wheel which specifically serve as a bottom for the die, as above referred to.

Journalized in bearings 50 supported on the bed plate 1 is a transverse shaft 51 designed to be rotated by means of a spiral gear 52 meshing with a similar spiral gear (not shown) carried by the drive shaft 7. Carried by the forward end of the shaft 51 is a cam 53 operating on a rocker arm 54 pivoted intermediate its ends to the frame 25 3. A rack 55 is slidably received within the bearing plate 46 and is connected to the upper end of the rocker arm 54, operation of the rocker arm 54 against the tension of the spring 56 imparting horizontal movement to the rack 55. A small transverse shaft 57 is journalized in bearings 30 on the underside of the table 26 and carries on its forward end a pinion 58 meshing with the teeth of the rack 55. The opposite end of the shaft 57 has fixed thereto a folding tongue 59. As the 35 male die 34 commences its recession from the female die 36, the cam 53 is so timed in its rotation as to operate the rocker arm 54 thereby to impart horizontal movement to the rack 55. Such movement of the rack rotates the pinion 58 and its shaft 57 so that a like rotation is imparted to the tongue 59 in which rotation the tongue 59 encounters the short vertical portion of the blank and in its continued rotation presses said portion from a vertical to a horizontal plane to overlie 45 the bottom portion of the blank thereby folding inwardly a portion of the printed matter so that the printed matter borne solely by the short vertical portion and the horizontal portion is placed in confronting face-to-face obscured relation. 50 Rotation of the folding tongue 59 is limited to a movement approximating 90° and is maintained in folding relation with the blank until such time as the blank is removed from registering relation with the forming die. At this point, it 55 may be stated that one side wall of the forming die is offset to form a sharp angle 60, the angle engaging the longer vertical portion of the blank so as to strip the blank from the male die 34 when the latter recedes.

Additional means for assisting in stripping the blank from the die is afforded by vacuum force, said force being applied to the under surface of the horizontal portion of the formed blank through passageways 112 provided in the feed 65 wheel 48. One passageway 112 is provided for each flat surface 49, one end of the passageway terminating at the flat surface and the opposite end opening outwardly at the front face of the feed wheel 48. The last mentioned opening is 70 designed to register with a vacuum line 113 provided in the bearing plate 46 and leading therefrom direct to the vacuum tank 25. Manifestly, as the feed wheel is intermittently rotated, the passageways 112 are successively positioned in 75

registering relation with the vacuum line 13 for exerting force to the under side of the formed blank.

The formed blank is removed from the die mechanism and is further folded by the following described mechanism: A ratchet 61 is carried by the shaft 47 exteriorly of the bearing plate 46 having associated therewith a pawl 62 operated by a connecting rod 63 associated with an eccentric 64 fixed to the outer end of the transverse shaft 51. The ratchet 61 has teeth in a number corresponding with the number of plane surfaces 49 in the feed wheel 48. In the upward throw of the eccentric 64 the pawl 62 engages the ratchet 61 thereby imparting an intermittent counterclockwise rotative movement to the shaft 47 and the thereby carried feed wheel 48. In such rotatory movement of the feed wheel 48 the abrupt shoulder terminating the plane surface 49 underlying the die engages the creased edge of the already folded portion of the blank and the partially formed blank is forced into the intervening space between the feed wheel 48 and the segmental chute or guide 65 which houses a portion of the feed wheel thereby forcing the longer vertical portion of the blank to be pressed downwardly substantially in the arc of a circle, the upper terminal of said portion being the last to enter the guide, and said longer portion abutting 30 the guide 65 in its travel. Intermittent rotary movement is thus imparted to the feed wheel 48 so that as each successive blank is further folded it is introduced in and received by the guide 65, the formed and folded blanks being moved 35 through the guide 65 by the shoulders of the flat surfaces 49 engaging the first folded edge of the blank. As shown in Figs. 7 and 9 of the drawings, the blanks are delivered outwardly of the guide 65 at the lower end thereof and at a point approximately 180° from the entrance, being discharged on the underside of the feed wheel.

Located on the underside of the plate 66 of the frame 3 are spaced parallel guides 67 defining a slot in the plate 66 in which slot is received a sliding channel 68 having on the underside thereof of a depending lug 69 which is connected to a link 70 and a pivoted lever 71 which, in turn, is connected by a connecting rod to an eccentric 72 fixed on the shaft 51. Obviously, with the above described mechanism a reciprocating movement is imparted to the channel 68 upon rotation of the transverse shaft 51. The sliding channel is provided with vacuum openings 74 communicating with the vacuum line 75 leading to the operating valve 23. The sliding channel 68 has a width exceeding the width of the feed wheel 48 and receives the feed wheel 48 intermediate the vertical side walls thereof. The inner end of the sliding channel 68 has formed thereon an integral projecting tongue 76 and provided adjacent said end are two gripping fingers 77, each of which consists simply of a spring having one end thereof fastened to the channel 68 and is reversely curved so that the free end thereof is in pressure contacting relation with the face of the channel at the inner termination of the channel.

As a folded blank is discharged from the guide 65 it is deposited within the channel 68 underlying the feed wheel 48 at which time the operating mechanism is so synchronized that the channel 68 is slidably retracted to blank gripping position, the gripping fingers being sufficiently flexible to override the folded end portion of the blank. At the limit of the retracting stroke of the channel 75 68, the direction of travel of said channel is re-

versed and the channel is then moved forwardly, at which time vacuum is applied through the ports 74 and the blank, consequently, adheres to the channel. The folded portion, or forward end, of the blank occupies underlying relation with respect to said fingers 77 which latter serve to temporarily retain the blank in its folded relation and, additionally, assists in withdrawing the blank from the feed wheel.

The channel 68 upon being moved to its innermost position is momentarily maintained stationary by the action of the specific construction of the telescoping link 70, shown in Figs. 1 and 18. The upper end of the lever 71 has formed thereon a sliding collar 78 embracing the link 70 and being maintained on the link by means of a nut 80 threaded on the end of the link. Interposed between the collar 78 and the shoulder provided on the link 70 is a compression spring 79, the purpose of which is to normally maintain the collar 78 in contacting relation with the retaining nut 80. The link 70 is provided with a threaded extention 81 having a head 82 formed on the forward end thereof and adapted during operation to abut a limit stop 83 fastened to the frame 3. In operation forward movement of the sliding channel 68 is accomplished, as above described, by the like forward movement imparted to the link 70 by the lever 71 and eccentric 72. Said channel 68 is moved forwardly until such time as the head 82 abuts the limit stop 83, at which time forward movement of the channel and thereby carried blank ceases and the projecting tongue 76 of the same is momentarily held in stationary advanced position directly beneath a banding head 96, which will later be described. However, the collar 78 continues to move forwardly in telescoping relation with respect to the link 70 against the tension of the spring 79, this specific mechanism being provided so that uninterrupted operation of the various elements may be continued while the sliding channel and thereby carried blank is maintained stationary during the banding operation.

The preceding portion of the specification has been confined to the forming and folding of the blank, and following these operations the folded portion of the blank is permanently bound by an annular gummed paper band 84, attached by the mechanism which will now be described.

Permanently attached, as by means of bolts, to the bed plate 1 is a stationary pedestal 85 to the upper end of which is attached a semi-circular cam race 86. The upper end of the pedestal 85 is enlarged to form an integral annular flange 87, as shown in Fig. 11, and supports a Geneva gear 88 which is bolted to a hub 89 encircling the standard 90, the latter being formed integral with the pedestal 85. The upper end of the Geneva hub 89 is provided with an annular flange 91 and has bolted thereto a rotatable circular plate 92, to the upper face of which is bolted a stationary vacuum ring 93, the latter also encircling the standard 90, the circular plate 92 being intermittently rotated by the Geneva gear 88, as will later be described.

Provided on the upper face of the circular plate 92 adjacent the periphery thereof are a plurality of upwardly extending guide pins 94, between each two adjacent pins is received a banding head housing 95 which carries a banding head 96 of inverted T-shape whose upper shank portion 97 is slidably received within a vertical extending channel 98 provided in the face of the housing and extending throughout the height 75

of the latter. The upper portion of the shank 97 is maintained in position within the channel 98 by a plate 107 bolted to the face of the housing. A compression spring 108 is located in said channel and is interposed between the upper end of the shank 97 and a plate 109 fastened to the top of the housing and serving as a top closure for the upper end of the channel. A roller 110 is attached to the rear of the housing adjacent the 10 top for a purpose to be later explained.

Provided in the bottom of the banding head 96 are two spaced recesses 99 in which are received a pair of banding rollers 100 carried on the lower end of banding arms 101, the upper ends 15 of said banding arms being fixed to short shafts 102 extending through the housing and carrying on their inner ends pinions 103, the teeth of which mesh with the teeth of a vertically movable rack 104 formed integral with a stem 105 extending 20 downwardly through the plate 92, the lower extremity of the stem 105 carrying a roller 106. The bottom of the banding rollers 100 in inoperative position are located in aligned relation with the lowermost face of the banding head 96.

25 As shown in Fig. 11, the banding head housing 95 has an offset or recessed concavity at its front lower end and the banding head 96 occupies a depending position in said concavity, the banding arms 101 being suspended intermediate the banding head 96 and housing 95, the rollers 100 extending forwardly from said arms 101 so as to be received within the two recesses 99 of the head.

The banding strip 84, having the under side thereof provided with gummed adhesive is severed from a length of paper 114 furnished to the machine from a spool supported on the bed plate 1 at the rear of the machine. Paper from the spool is presented to the shearing mechanism by a feeder permanently mounted on a base plate 115 suitably supported by the frame 3. As shown in detail in Figs. 16 and 17, a feeder block 116 is permanently attached to the base plate 115 and has a slot 117 extending throughout its length at the top thereof. Slidable in said slot 117 is a 40 feeder jaw 118 having a downwardly extending lug 119. Pivotedly attached to said lug is one end of a short connecting link 120, the opposite end of said link being connected to a rocker shaft 121, the opposite ends of the shaft being journaled in 45 bearings provided on the lower ends of upwardly projecting spaced arms 122. Said arms 122 are supported by and slidable on spaced parallel rods 123 whose opposite ends are received in and supported by the feeder block 116. The opposite 50 ends of the rocker shaft 121 are provided with crank arms 124 pivotally connected to the upper ends of levers 125, the lower end of said levers 125 being provided with rollers adapted to contact cams 126 carried by the shaft 7, and being 55 supported intermediate its ends by a stationary shaft 127, which latter is carried by the frame 3.

Carried by the upper ends of the arms 122 at a spaced distance above the feeder block 116 is a 60 plate 128 having formed integrally therewith on the under side thereof a downwardly extending rib 129 overlying the feeding jaw 118 and adapted to cooperate therewith as will later be explained.

Spaced parallel paper guides 130 are provided 70 along the top of the feeder block 116 adjacent the sides thereof, and located intermediate the guides 130 and the opposite sides of the feeder jaw 118 are paper depressing plates 131, the rear end of said plates 131 being connected by a cross 75 bar 132 whose opposite ends rest upon the guides

130 and are apertured to embrace studs 133 projecting from the feeder block 116.

Spring pressed shoes 134 provided intermediate the paper depressing plates 131 and the top plate 128 are adapted to maintain said depressing plates 131 in permanent contacting relation with the paper 114.

The length of gummed paper 114 is supplied to the shears 135 by the above described mechanism as follows: Paper 114 is supplied from the spool to the feeder head 116 where it occupies a position overlying the jaw 118; underlying the rib 129 and intermediate the guides 130. Rotation of the cam 126 acting on the lever 125 imparts counter clockwise motion to the crank arms 124, 15 shaft 121 and thereby carried link 120. Such movement initially elevates the jaw 118 so that the serrated upper face thereof grips the under, or gummed, surface of the paper 114, and continued forward movement of the upper end of 20 the lever 125 imparts a like forward movement throughout a predetermined distance to the entire gripping and feeding mechanism carried by the slidably supporting arms 122 to position the required length of paper to the shears for cutting. 25 Following such advance movement, the direction of the travel of the lever 125 is reversed, the gripping jaw 118 being thereby disengaged from the paper and the feeding mechanism being retracted, the paper 114 being maintained in stationary advanced position by the depressing paper contacting plates 131.

Provided on the forward end of the feeder block 116 are a pair of spaced upwardly extending posts 135 serving as guides for a vertically reciprocable shear block 136 adapted to be lowered by means of the link and lever mechanism 137 acted upon by the cam 138 carried by the shaft 7 and elevated by the retractile springs 139. A cutter blade 140 is carried by the shear block 136 40 while a cooperating stationary cutter blade 141 is mounted on the forward end of the feeder block 116.

Slidable in channel guides 142 on the under side of the base plate 115 is a carrier plate 143 having a hollow upwardly extending standard 144 located on its forward end. A vacuum line 145 has one end connected to the standard 144 and the opposite end connected to the valve 23. Forward and rearward reciprocation is imparted to the carrier plate 143 by means of a link and lever mechanism 146 acted upon by a cam 147 carried by the shaft 7, the lower end of the lever being pivotally connected to the bed plate 1 and the link being connected to the plate 143 by a 50 downwardly extending lug 148.

Simultaneously with the advancement of the paper supply 114 to the shear blade 140, the carrier plate 143 and standard 144 is moved toward the shear to occupy approximate underlying relation to the same. Following the furnishing of a predetermined length of paper 114 to the shears, the feeding mechanism is retracted, as hereinbefore described, and the shear housing 136 and thereby carried blade 140 is lowered to sever from the paper a banding strip 84, which strip is then supported on the upper end of the standard 144. Vacuum is then applied to the standard 144 through the line 145 so as to retain the band thereon. At this point the shear is elevated to 60 inoperative position by the springs 139, and immediately thereafter the standard 144 carrying the strip 84 is moved forwardly to a position where it directly underlies one of the banding heads 96 mounted on the intermittently rotatable plate 92. 75

Vacuum to the standard 144 is then released and vacuum is instead applied to the overlying banding head 96 through a line 149 connecting with the rotating vacuum ring 150 attached to the intermittently rotatable plate 92 and encircling the stationary vacuum ring 93.

The rotating vacuum ring 150 is provided with a plurality of radially disposed vacuum ports 151 in a number equal to the number of banding head units carried by the rotatable plate 92, the inner ends of said ports 151 terminating at the meeting point with the stationary vacuum ring 93 and the outer ends thereof being connected to a line 149 leading to each banding head unit.

The inner, or stationary vacuum ring 93 is fixed in non-rotatable relation and is provided with a single isolated port 152 whose sole function is to supply vacuum to that particular banding head unit of the series which, in the progressive operation of the machine, is due to receive a severed banding strip 84 prior to the banding operation. The port 152 is supplied with vacuum through the line 153 leading to the vacuum control valve 23 so that vacuum is applied to the banding head only at predetermined intervals, as when a banding strip 84 is to be transferred from the carrier standard 144 to a banding head. As is obvious, during transfer of the strip 84 the isolated port 152 of the stationary ring is in registering communicating relation with the port 151 of the rotatable ring 150 leading to the vacuum passageway 156 provided interiorly of the banding head 96 and shank 97 of the specific banding unit which is to receive the strip. Of necessity, the gummed banding strip 84 must be held in adhering relation to the under side of the banding head 96 during progressive intermittent rotation of the plate 92 from the station at which transfer of the strip is effected until the banding station is reached which approximates a 90° rotation of the plate 92. This is accomplished by providing in the stationary ring 93 a segmental vacuum recess 154 throughout 90° of the extent of said ring. Vacuum is continuously furnished to the recess 154 by a line 155 having direct connection with the vacuum tank 25. Manifestly, as the ports 151, connecting with the passageway 156 of each banding head unit, are in communicating relation with said recess, vacuum is applied to each affected banding head to retain the strip 84 in position.

Intermediate the strip transferring station and the banding station, the gummed adhesive provided on the under side of the strip 84 is moistened by a wick 157 carried by a vertically reciprocable stem 158 supported on the frame 3 and actuated by a cam 159 carried by the shaft 7. Operation of the cam 159 is such that the wick 157 is elevated to contact and moisten the adhesive of the band in predetermined timed relation to the intermittent rotation of the plate 92.

Following moistening of the adhesive, the head and thereby carried strip 84 is intermittently and progressively advanced by rotation of the plate 92 to the banding station, which station is in alignment with the blank positioning channel 68 of the blank feeding mechanism. As previously explained, the blank positioning channel 68 carrying the formed and folded blank 10 is advanced and momentarily held stationary in such advanced position (by mechanism previously explained in detail) so that the folded portion of the blank 10 is positioned directly beneath a banding head 96 and previously moistened strip 84 carried thereby, the folded end portion of the blank

10 being supported in underlying relation by the forwardly projecting tongue 76 of the channel 68.

Permanently fixed on the standard 90 adjacent the upper end thereof is an upper cam race 160, circular in top plan, whose front portion, or approximately 180°, has a plane surface parallel with the upper face of the lower cam race 86, the rear portion, or remaining 180°, of the upper cam race 160 being convexly curved.

Supported in fixed position on the upper end of the standard 90 at a spaced distance above the upper cam race 160 is the head of a T-shaped supporting plate 161, the rearwardly extending blade thereof being supported by the shear guide posts 135.

Journaled in bearings 162 located on the plate 161 is a rocker shaft 163, the front end of said shaft having mounted thereon a walking beam 164, and the rear end having fixed thereto one end of a rocker arm 165, the opposite end being pivotally connected to a depending link 166 adapted to have reciprocal movement imparted thereto by a cam 167 mounted on a transverse shaft 168, said shaft being driven by the front shaft 4 through spiral gears 169.

Bearings 170 are provided on the opposite ends of the head of the T-shaped supporting plate 161 and are adapted to receive therein plunger pins 171 and 172 depending from the opposite ends of the walking beam 164.

Simultaneously with the advancement of the blank positioning channel 68 beneath the banding head unit bearing the strip 84 to be applied to the blank 10, the walking beam 164 is oscillated in such manner as to forcibly move the plunger pin 171 downwardly through its bearing 170 so that the lower end of said pin strikes the roller 110 of the banding head unit thereby forcing the entire unit downwardly against the tension of the supporting spring 173 to position the thereby 40 borne banding strip 84 in overlying contacting relation with the previously positioned folded portion of the blank 10, said blank being located midway between the opposite ends of the banding strip, as illustrated in Fig 12. In such position, the banding head 96 and its shank 97 is immovably supported on the tongue 76 of the channel 68, and thereafter continued downward movement of the unit is confined to the housing 95, arms 101 and stem 105, the shank 97 telescoping within the channel 98 of the housing 95 against the tension of the spring 108, as shown in Fig. 11. Such continued downward movement of said elements results in the banding rollers 100 being brought out of housing relation 55 within the recesses 99 and, as a consequence, the opposite ends of the banding strip 84 are turned downwardly at right angles to the horizontal portion overlying the fold of the blank 10.

Depression of the above elements is also resisted by a plunger post 174 slidably mounted in an appropriate supporting member 175 attached to the bed plate 1, said post 174 being normally supported in elevated position by a retractile coil spring 176 having one end thereof attached 65 to a pin projecting from the post and the opposite end attached to the frame 3.

When the banding rollers 100 are lowered to a point below the level of the blank 10, said rollers 100 are thereby rendered free and non-confined 70 and, as a result, the force exerted on the spring 176 through depression of the post 174 is released, causing the spring to instantly retract and suddenly force upwardly the post 174 and thereby supported stem 105. Upward movement of the 75

stem 105 results in like movement being imparted to the integral rack 104 which acts to rotate the pinions 103 thereby swinging the arms 101 and thereby carried rollers 100 toward each other, causing the depending free ends of the strip 84 to be brought inwardly and upwardly into underlying, adhering banding relation with the folded portion of the blank, this operation completing the placing of an encircling annular band about the folded portion of the blank. The banding strip 84 is of such length that the opposite ends thereof terminate at each side of the blank supporting tongue 76 so that the latter is not included within the embrace of the banding strip. 10

Following completion of the banding operation, the channel 68 and its tongue 76 is retracted to receive another blank 10, and the plate 92 and thereby carried banding units are rotated a pre-determined distance by the Geneva 88. In such 15 rotation, the rollers 110 and 106 are brought into contacting relation with the confronting faces of the upper and lower cam races 160 and 86, respectively, as partially shown in Fig. 1, this being responsible for maintaining the banding head 20 elements in banding position wherein the rollers 100 occupy underlying relation to the opposite 25 ends of the banding strip 84.

The banding head elements are maintained in the above described position throughout approximately 180° of rotation of the plate 92, this permitting sufficient time to elapse to permit drying of the adhesive of the banding strip 84. Upon reaching a point diametrically opposite to the banding station the banding head unit is subjected to ejecting apparatus for releasing the banded blank from the banding head unit. This apparatus consists of a yoke 177 carried on the lower end of the pin 172 of the walking beam 164 and adapted to engage the upper roller 110. 30 A somewhat similar yoke 178 is carried by one end of a lever 179 pivoted intermediate its ends to the frame 3 and has its opposite end provided with a roller 180 adapted to engage a cam 181 carried by the transverse shaft 168. As said 35 banding unit reaches the ejecting station, the lower roller 106 is engaged by the yoke 178, which yoke is moved downwardly by means of the lever 179 and cam 181 to bring the stem 105 and rack 104 downward for returning the banding arms 50 101 to retracted position whereby the blank 10 is freed and unsupported, falling from the banding unit to a revolving table 182.

Immediately following discharge of the blank, as aforesaid, the yoke 177 engages the upper roller 55 110 and the end of the walking beam 164 carrying the pin 172 is elevated, this elevation returning all of the banding elements upwardly on their guides 94 to inoperative retracted position, as the latter are shown in Fig. 12 and at the 60 right in Fig. 11.

As previously stated, the lower cam race 86 is semi-circular in top plan having its terminal ends located at the banding station and discharge station, respectively. As the banding 65 unit, due to continued rotation of the plate 92, leaves the discharge station, the lower roller 106 is unsupported and the upper roller 110 engages the convexly curved portion of the upper cam race 160 so that the banding head unit as a whole 70 is lowered so as to be in position to receive a severed banding strip 84 from the shears, as aforesaid.

Intermittent rotary movement is imparted to the plate 92 supporting the banding units by the 75 Geneva gear 88 adapted to be intermittently en-

gaged by a Geneva crank 182 carried by the upper end of a vertical shaft 183 suitably journaled in a bearing 184 attached to and supported by the upper end of the pedestal 85. Said shaft 183 is driven by a thereby carried spiral gear 185 meshing with a similar spiral gear 186 carried by the transverse shaft 168.

While a revolving table 182 has been shown in the drawings as being adapted to receive the finished product of the machine, it will be understood that this mechanism forms no pertinent part of the invention inasmuch as various forms of receptacles and conveyors may be utilized to receive the finished product. For this reason, it is not thought necessary to herein describe the 15 actuating means for revolving the table 182 or further refer to the same.

It will be understood that a blank 10 is formed with each complete reciprocation of the die plunger 34 and that a flat surface 49 of the feed 20 wheel 48 is successively advanced to underlying relation to the forming die with each reciprocation of said die. Furthermore, a folded blank is presented to a banding head unit for banding with each reciprocation of the blank-advanc- 25 channel 68.

As revealed by the drawings, the entire circular rotating plate 92 has its entire circumferential extent provided with a plurality of banding head units, the latter occupying side-to-side 30 relation. Each individual unit is successively supplied with a gummed banding strip 84; receives a folded blank 10 to be banded when presented to the banding station; bands the same; retains the banded blank for a period of time sufficient 35 to permit the adhesive to dry, and finally releases the finished product at the discharge station. The operation of the machine is continuous and operates at high speed, it being possible to form, fold and band in excess of one hundred blanks 40 per minute without undue strain and/or injury to the machine.

The various shafts and cams are manufactured and assembled with precision so that all movements are synchronized to avoid any interruption 45 of operation or improper functioning of the machine. The valve controlling the vacuum supply to a portion of the parts is a multiple valve and is operated by a cam 187 carried by the transverse shaft 168 so that vacuum is supplied thereto 50 only at predetermined desired intervals.

While the invention more particularly is designed for the production of banded blanks for use with gaming boards, nevertheless it is equally adapted for use in the production of banded 55 blanks for other purposes and hence is not so limited.

What is claimed is:

1. A strip feeding and folding machine of the character described, including a table having an 60 opening therethrough, a strip receiving hopper above said table, means for removing a strip from said hopper and depositing same upon the table, means for advancing a strip along said table and into position over said opening, a reciprocating die above said table aligned with the opening and adapted for movement therethrough, a feed wheel beneath said opening adapted to cooperate with said die member to form said strip into substantially U-shape with one free end 65 shorter than the other, means supported by the table beneath the latter for folding the short end of the strip into parallel relation with the bight portion of same, a stationary guide member cooperating with the feed wheel for fold- 70 75 75

5 ing the long end of the strip into parallel relation with the bight portion and the other end of the strip, mechanism for securing the folded portion of the strip in folded position, a reciprocating channel member for advancing the folded blank to the securing mechanism, and power means for actuating all of said moving elements in timed sequence.

10 2. A strip feeding and folding machine of the character described, including a movable die member, a feed wheel cooperating with said die member for forming a strip into substantially U-shape with one free end shorter than the other end, means between said die and wheel for folding said short end of the strip into parallel relation with the bight portion of the strip, and a channeled guide member cooperating with said wheel for folding the other end of the strip into parallel relation with the previously folded portion of the strip, said last named end terminating a predetermined distance beyond the folded portion of the strip to provide a supporting tab.

15 3. A strip feeding and folding machine of the character described, including a movable die member, a feed wheel beneath and cooperating with said die member for forming a strip into substantially U-shape with one free end shorter than the other end, means between said die member and wheel for folding said short end of the strip into parallel relation with the bight portion thereof, and means for folding the other end of the strip into parallel relation with said previously folded portion of the strip.

20 4. A strip feeding and folding machine of the character described, including a movable die member, a feed wheel beneath and cooperating with said die member for forming a strip into substantially U-shape with one free end shorter than the other end, means between said die member and wheel for folding said short end of the strip into parallel relation with the bight portion thereof, means for folding the other end of the strip into parallel relation with said previously folded portion of the strip, and means for securing the folded portion of the strip in folded position.

25 5. A strip feeding and folding machine of the character described, including a movable die member, a feed wheel cooperating with said die member for forming a strip into substantially U-shape with one free end shorter than the other end, means between said die and wheel for folding said short end of the strip into parallel relation with the bight portion of the strip, and a stationary arcuate member cooperating with said wheel for folding the other end of the strip into parallel relation with the previously folded portion of the strip, said last named end terminating a predetermined distance beyond the folded portion of the strip to provide a supporting tab.

30 6. A strip feeding and folding machine of the character described, including a table having an opening therethrough, a substantially rectangular die member positioned above and aligned with the opening and adapted for movement through the latter, feed means beneath the opening having spaced plane surfaces cooperating with said die member for forming a strip into substantially U-shape with one free end of the U-shaped strip shorter than the other end thereof, means for folding said short end of the strip parallel to the bight portion of the same, means cooperating with the feed means for folding the long end of the strip into parallel relation with the

35 bight portion and short end of the strip, means for securing the folded portion of the strip in folded position, and means for advancing the folded strip from the feed means to the securing means.

40 7. A strip feeding and folding machine of the character described, including a table having an opening therethrough, a die member aligned with the opening and adapted for movement through the latter, means for positioning a strip over said opening and beneath the die member, means beneath the table and aligned with said opening and cooperating with the die member for forming a strip into substantially U-shape, one of the walls defining the opening being formed with an offset shoulder to engage one side of the strip for removing the latter from the movable die member during one movement of the latter, and means beneath the table for folding the sides of the strip into overlapping parallel relation.

45 8. A blank feeding and folding machine of the character described, including means for forming a blank into substantially U-shape, means for folding the ends of the blank into parallel relation with the bight portion thereof, and means for disposing a retaining band about the folded blank in embracing relation thereto, including a banding head, banding rollers carried by said head and means carried by said head for simultaneously actuating the rollers to disposed said band about said folded blank.

50 9. A blank feeding and folding machine of the character described, including means for forming a blank into substantially U-shape, means for folding the ends of the blank into parallel relation to the bight portion thereof, means for feeding a retaining band to a position overlying said folded blank and for folding the same about the latter, including a banding head, movable forming means carried by said head, means carried by said head for actuating the forming means for releasing said blank and band from the banding head.

55 10. A strip feeding and folding machine of the character described, including a table having an opening therethrough, a substantially rectangular die member aligned with the opening and adapted for movement through the latter, means beneath the table and cooperating with the die member for forming said strip into substantially U-shape, one of the walls defining the opening being formed to frictionally remove the U-shaped strip from the movable die member during the receding movement of the latter, means beneath the table for folding the ends of the strip into parallel relation with the bight portion of the latter, means to secure the folded strip in its folded position, and means for advancing the folded strip to the securing means.

60 11. A strip feeding and folding machine of the character described, including means for folding the strip, means for feeding the strip to said folding means, mechanism for securing the strip in folded position, means for feeding the folded strip to said securing mechanism, said securing mechanism including a banding head, means associated with the head for positioning a retaining band above said folded strip, means for moving the banding head and band into engagement with said folded strip, and means carried by said banding head for forming and moving said band into embracing relation with the folded strip.

65 12. In an apparatus of the character described, means for folding a predetermined portion of a

rectangular strip upon itself, means for permanently securing said folded portion in folded position, means for transferring said strip from said folding means to said securing means, and means including a revolving feed wheel for delivering said strip to said transferring means from said folding means.

13. In an apparatus of the character described, means for folding a predetermined portion of a strip upon itself, means for permanently securing said folded portion in folded position, means for transferring said strip from said folding means to said securing means, means including a revolving feed wheel for delivering said strip to said transferring means from said folding means, and means borne by said transferring means whereby said strip is temporarily maintained in its folded position during its transmission to the permanent securing means.

14. In an apparatus of the character described, means for folding a predetermined portion of a strip upon itself, means for permanently securing said folded portion in folded position, reciprocating means for transferring said strip from said folding means to said securing means, means including a revolving feed wheel for delivering said strip to said transferring means from said folding means, and means for interrupting the reciprocation of said transfer means during the operation of permanently securing the folded portion of said strip.

15. A strip feeding and folding machine of the character described including a table having an opening therethrough, a die member positioned above and aligned with the opening and adapted for movement through the latter, feed means beneath the opening having spaced plane surfaces cooperating with said die member for forming a strip into substantially U-shape, movable means for folding one vertical portion of said strip into parallel face-to-face contacting relation with the horizontal portion thereof, and a channeled stationary guide member cooperating with the feed means for folding the other vertical portion of the strip into parallel relation with the other two portions of the strip.

16. A strip feeding and folding machine of the character described including means for forming a strip into substantially U-shape, means for forming the opposite ends of the strip into parallel relation with the bight portion thereof, and means for disposing a retaining band in embracing relation to said folded strip, said last mentioned means comprising a banding head adapted to position a retaining band in overlying relation to said folded strip, banding arms carried by said head, and means carried by said head for actuating said arms to dispose said band in embracing relation about said strip.

17. In an apparatus of the character described, means for folding a portion of a strip upon itself, and means for disposing a retaining band in embracing relation to said folded strip, said last mentioned means comprising a banding head adapted to position a retaining band relative to said strip, pivoted banding arms carried by said head, and actuating means borne by said head whereby said arms are rotated toward each other to dispose said retaining band in embracing relation about said folded strip.

18. A strip feeding and folding machine of the character described including means for folding a strip, means for feeding the strip to said folding means, mechanism for securing the strip in folded position, means for feeding the folded strip

to said securing mechanism, said securing mechanism including a banding head, vacuum means supplied to said head for causing adherence of a retaining band thereon and for subsequently positioning said band above said folded strip, means for moving the banding head and band into engagement with said folded strip, and means carried by the head for forming said band into embracing relation with the folded strip.

19. A blank feeding and folding apparatus of the character described including means for folding a portion of a blank about itself, a banding head for positioning a thereby-carried retaining band about said folded blank, a carrier for positioning said folded blank beneath said banding head, means for moving said banding head and band into engagement with said blank, and pivoted arms borne by said head whereby upon actuation thereof said band may be formed into embracing relation with said blank.

20. A blank feeding and folding apparatus of the character described including means for folding a portion of a blank about itself, a banding head for positioning a thereby-carried retaining band about said folded blank, pivoted banding arms carried by said head, a carrier for positioning said folded blank beneath said banding head, means for lowering said banding head and band into contacting relation with said blank, said band being deposited on said blank in a horizontal plane with its opposite ends extending beyond said blank, means for further lowering a portion of said head and banding arms to dispose the free ends of said band in depending vertical positions, and means for rotating said banding arms toward each other to dispose said ends of the band in parallel relation with the under side of said blank.

21. A blank feeding and folding apparatus of the character described including means for folding a portion of a blank about itself, a banding head for positioning a retaining band about said folded blank, pivoted banding arms mounted on shafts journaled in said head, gears carried by said shafts and meshing with a rack supported by said head, means for lowering said head and band into engagement with said blank, means for further lowering said banding arms below the plane of said blank, and means for actuating said rack for rotating said arms toward each other for forcing said band into embracing relation with said blank.

22. A blank feeding and folding machine of the character described including means for folding a portion of a blank about itself, a banding head for positioning a thereby-carried retaining band about said folded blank, a carrier for positioning said folded blank beneath said banding head, means for moving said banding head and band into contacting relation with said blank, pivoted arms borne by said head whereby upon actuation thereof said band may be formed into embracing relation with said blank, and means for returning said head and actuating said arms to assume inoperative position for effecting release of the banded blank from the banding head.

23. In an apparatus of the character described, means for folding a portion of a strip about itself, means for disposing a retaining band in embracing relation to said folded strip, said last mentioned means being supported by a rotating table, and means for intermittently rotating said table to position said banding means to receive the folded strip as it is transferred thereto from said folding means.

24. A blank feeding and folding apparatus of the character described including means for folding a portion of a blank about itself, means for securing said blank in folded relation consisting of a plurality of banding heads for disposing a retaining band about said folded portion, a turntable supporting said banding heads, means for transferring a blank from said folding means to one of said banding heads, and means for intermittently rotating said turntable to successively position a banding head in registering relation with said transfer means for receiving a folded blank. 5
25. A blank feeding and folding apparatus of the character described including means for folding a portion of a blank about itself, means for securing said blank in folded relation consisting of a plurality of banding heads supported on a turntable for disposing a retaining band about said folded portion, means for transferring a blank from said folding means to one of said banding heads, means for intermittently rotating said turntable to successively position a banding head in registering relation with said transfer means for receiving a folded blank, and means whereby a retaining band may be positioned on and carried by each of said banding heads during rotation of said turntable and prior to reaching said transfer means. 10
26. In an apparatus of the character described, means for folding a portion of a blank about itself, a plurality of banding heads carried by and vertically movable on an intermittently rotated turntable for positioning a retaining band about each of the folded blanks as the latter are folded, a carrier for positioning the successively folded blanks beneath successively presented banding heads, means for moving each of said banding heads and thereby-carried retaining band into engagement with a folded blank when presented thereto by the carrier, banding means borne by each of said heads whereby upon actuation thereof said band and banding means are brought into embracing relation with the folded blank. 15
27. In an apparatus of the character described, means for folding a portion of a blank about itself, a plurality of banding heads carried by and vertically movable on an intermittently rotated turntable for positioning a retaining band about each of the folded blanks as the latter are folded, a carrier for positioning the successively folded blanks beneath successively presented banding heads, means for moving each of said banding heads and thereby-carried retaining band into engagement with a folded blank when presented thereto by the carrier, banding means borne by each of said heads whereby upon actuation thereof said band and banding means are brought into embracing relation with the folded blank, and means for retaining said banding means in embracing relation to said blank during a predetermined period of continued rotation of said turntable. 20
28. In an apparatus of the character described, means for folding a portion of a blank about itself, a plurality of banding heads carried by and vertically movable on an intermittently rotated turntable for positioning a retaining band about each of the folded blanks as the latter are folded, a carrier for positioning the successively folded blanks beneath successively presented banding heads, means for moving each of said banding heads and thereby-carried retaining band into engagement with a folded blank when presented thereto by the carrier, banding means borne by each of said heads whereby upon actuation thereof said band and banding means are brought into embracing relation with the folded blank, and means for retaining said banding means in embracing relation to said blank during a predetermined period of continued rotation of said turntable. 25
29. In an apparatus of the character described, means for folding a portion of a blank about itself, a plurality of banding heads carried by and vertically movable on a rotating turntable for positioning a retaining band about each of the folded blanks as the latter are folded, a reciprocating carrier for positioning the successively folded blanks beneath successively presented banding heads, means for moving each of said banding heads and thereby-carried retaining band into engagement with a folded blank when presented thereto by the carrier, pivoted banding means borne by each of said heads whereby upon actuation thereof said band is brought into embracing relation with the folded blank, means for interrupting rotation of the turntable and means for interrupting reciprocation of the carrier during banding of the blank. 30
30. A strip folding and feeding machine of the character described including a vertically reciprocable die member, a feed wheel having spaced plane surfaces beneath and cooperating with said die member for forming a strip into substantially U-shape, means between said die member and wheel for folding one end of the strip into parallel face-to-face contacting relation with the bight portion thereof, means for folding the other end of the strip into parallel contacting relation with said previously folded portion of the strip, and radial extending passageways provided in said feed wheel terminating at the plane surfaces thereof whereby the strip may be caused to adhere to said wheel upon the introduction of suction force through said passageways. 35
31. A strip feeding and folding machine of the character described including a vertically reciprocable die member, a feed wheel having spaced plane surfaces of shallow depth formed integrally with said wheel cooperating with said die member for forming a strip into substantially U-shape, means between said die member and wheel for folding one end of the strip into parallel face-to-face contacting relation with the bight portion thereof, and means for folding the other end of the strip into parallel relation with said previously folded portion of the strip. 40
32. A strip feeding and folding machine of the character described including a vertically reciprocable die member, a feed wheel beneath and cooperating with said die member for forming a strip into substantially U-shape, means between said die member and wheel for folding one end of the strip into face-to-face contacting relation with the bight portion thereof, and means for folding the other end of the strip into parallel relation with said previously folded portion of the strip, and means for disposing a retaining band in embracing relation to said folded strip for maintaining the same in folded relation. 45
33. A strip feeding and folding machine of the character described including a table having an opening therethrough, a strip receiving hopper above said table, means for removing a strip from said hopper and depositing the same upon the 50
- 75

table, means for advancing a strip along said table and into position over said opening, a reciprocating die aligned with said opening and adapted for movement therethrough, a feed wheel beneath said opening adapted to cooperate with said die member to form the strip into substantially U-shape, means between said die member and wheel for folding one end of the strip into parallel contacting relation with the bight portion thereof, and means for folding the other end of the strip into parallel relation with said previously folded portion of the strip.

34. A strip feeding and folding machine of the character described including a table having an opening therethrough, means for positioning a strip upon the table overlying said opening, a reciprocating die aligned with said opening and adapted for movement therethrough, a feed wheel beneath said opening adapted to cooperate with said die member to form the strip into substantially U-shape, means supported from said table for folding one end of the strip into parallel contacting relation with the bight portion thereof, and means for folding the other end of the strip into parallel relation with said previously folded portion of the strip.

35. A strip feeding and folding machine of the character described including a table having an opening therethrough, a reciprocable die member aligned with said opening and adapted for reciprocable movement therethrough for forming a strip into substantially U-shape, a feed wheel beneath said die member and cooperating with the latter for forming said strip, means supported from said table between said die member and wheel for folding one end of the strip into face-to-face contacting relation with the bight portion thereof, and means for folding the opposite end of the strip into parallel relation with said previously folded portion of the strip. 5 10

36. A strip feeding and folding machine of the character described including a reciprocable die member for forming a strip into substantially U-shape, a feed wheel having peripheral serrations cooperating with said die for forming said strip, means between said die member and wheel for 20 folding one end of the strip into face-to-face contacting relation with the bight portion thereof, and means for folding the other end of the strip into parallel relation with said previously folded portion of the strip. 25
